UNITED STATES PATENT OFFICE.

CHARLES HAMMER, OF HOLLIS COURT BOULEVARD, NEW YORK.

METAL CAP OR CLOSURE.

Refiled for abandoned application Serial No. 714,143, filed August 8, 1912. This application filed December 8, 1922. Serial No. 605,919.

To all whom it may concern:

Be it known that I, CHARLES HAMMER, a citizen of the United States, residing at Hollis Court Boulevard, in the county of Queens and State of New York, have invented certain new and useful Improvements in Metal Caps or Closures, of which the following is a specification.

This invention relates to bottle caps or closures of the type particularly intended for use with a bottle or jar having a plurality of separated spiral threads.

The principal object of the invention is to provide improved means at the lower edge of the cap for engaging the separated spiral threads of the jar or bottle.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings forming part of this specification Fig. 1 is a side elevation, partly in vertical section, of a bottle cap or closure constructed in accordance with the present invention; Fig. 2 is a fragmentary view in perspective, showing the manner in which the lower edge of the cap is bent inward, and the adjacent portion of the flange slit, to form an engaging member for the separated threads of the bottle; Fig. 3 is a vertical section through the upper end of the bottle or jar; and Fig. 4 is a bottom plan view of the cap or closure.

Like reference numerals indicate corresponding parts in the several figures of the drawings.

The reference numeral 1 indicates the upper portion of a jar or bottle which is formed preferably with an annular rib 2 and a plurality of separated spiral threads 3 extending upwardly therefrom.

The numeral 4 indicates the cap or closure which is formed preferably with a flat top 5 and a depending annular flange 6. At its lower edge the flange 6 is rolled or curled as indicated at 7, a wire being shown therein at 8.

For the purpose of forming inward pro-

jections adapted to engage the separated spiral threads 3, the rolled edge 7 is bent inward at suitable points, as indicated at 9 in Figs. 2 and 4. Just above each bent-in portion 9, the flange 6 of the cap or closure is formed with a longitudinal slot 10 which serves to separate the metal of the flange from the bent-in portion of the wire edge. The bent-in portions 9 serve to engage the separated spiral threads of the jar and hold the cap or closure in position thereon. The flange 6 is preferably formed with vertical corrugations 11.

Among metal cap manufacturers a beaded, rolled, or curled edge cap has been commonly called a wire edge cap, presumably because the small rolled edge has the appearance of a wire, and while of course a wire within the rolled edge makes that edge more rigid, yet the fact is that this wire is not essential for this purpose as the bead 7 is strong enough to strengthen the cap and give the requisite stiffness to the in-bent portions 9 without the wire, as in my Patent, 1,160,596 of Nov. 16, 1915, filed Aug. 8, 1912, at the same time as the original application for the present improvement, and as in my prior Patents, 1,079,238 and 894,633, all filed before Aug. 8, 1912, and both of which show such rolled edges without said wire.

The provision of the slits located at intervals around the cap permits the curled, rolled or strengthened edge of the cap to be readily forced inward at such intervals the required distance to form locking projections, any desired number of which may be used. It will be observed that by the provision of these slits, shown located between the curled edge and the lower ends of the reinforcing corrugations, the curled edge can be readily forced inward to form such locking projections without any appreciable flexure of the skirt or flange of the cap, and by somewhat less pressure than would otherwise be required were these slits not present, while at the same time these inwardly extending locking projections constituting or forming a part of the rolled or beaded edge, may by reason of the slitting of the metal thereabove be forced inwardly sufficiently to take up the necessary variation in the glass jar and if desired without materially affecting the contour or circular cross section of the projection. That is to say, by slit-

ting the metal just above the rolled edge at intervals, the whole of this rolled edge may be forced inwardly at such slitted portions of the cap so that if desired the general 5 shape of the projections may remain substantially the same as the curled edge between the projections, although if an increased locking surface, either lengthwise or crosswise of the lug, is required, this may be 10 readily obtained by somewhat flattening the in-pressed portions so that the projections may be somewhat flattened either horizontally or vertically if preferred according to the character of the lug or divided thread of 15 the glass container with which the cap is to be used.

It will further be observed that the corrugations not only form a gripping surface but act to reinforce the metal of the skirt or 20 flange, not only around the same but also at the point where the metal is slit adjacent to the inwardly pressed locking projections.

Thus the primary object of the present 25 invention is the provision of a metal cap which may be made of relatively thin metal having a reinforced or strengthened edge comprising a curled, beaded, or rolled portion, a part of which may be readily in-pressed to form locking projections for a 30 divided thread glass container by a slitting of the metal of the cap flange adjacent to said in-pressed projections, thus permitting a part of said rolled edge to be utilized at intervals to form locking projections inwardly extending toward the center of the 35 cap.

Furthermore because the slits permit the 40 bead to be readily forced inward to form locking projections, these locking projections may join the bead without any defective deforming thereof, and consequently the cap on its outside has less the appearance of being deformed at these points than might otherwise be the case, so that the cap 45 flange has the appearance of having its general circular contour maintained. Furthermore on the principle that an arch is stronger than a flat wall, it follows that these hollow rounded locking projections 50 will effectively resist deformation on their application to the glass container, so that the present improved cap has not only a strengthened flange, due to the reinforcing corrugations, but a strengthened curled edge 55 and strengthened locking projections of general circular form, and in consequence the cap may be made as hereinbefore stated of relatively thin sheet metal. By the provision of the slits the rolled or strengthened 60 edge may be forced inwardly more sharply without, as hereinbefore stated, any appreciable deformation of the flange of the cap.

In forming this improved cap a cup-shaped blank is first provided and its flange 65 is provided with a strengthened edge by

forming thereon a roll, bead, or curl by some suitable means, thereby to eliminate the disadvantages of the raw edge which are considerable. Slits are then formed at the required intervals in the flange just above the 70 strengthened edge and the rolled edge is then forced inwardly adjacent to these slits to form the locking projections. During the formation of the rolled edge the flange may be also provided with the strengthening corrugations or these may be provided subsequently as may be desired. The several steps of forming the curl or roll, slits, corrugations and projections may in practice all take place substantially simultaneously on the same tools as, for instance, rolls provided with portions for forming the corrugations, portions for curling the edge, portions for deflecting the same inwardly, and portions for slitting the flange, except 80 that the portions for slitting the flange will operate slightly in advance of that part of the tools which project the rolled edge inwardly to form the locking projections.

In the application of the cap to the glass 90 container, especially when a hermetic seal is desired, a suitable liner is provided.

This improved closure is practical with any container having divided or multiple threads adjacent to the mouth of the same, 95 and I do not wish to be limited to the exact details of the construction herein set forth as the same may be varied, and I therefore reserve the right to change the shape, size, and arrangement of the parts without departing from the spirit and scope of my invention and the claims.

I claim as my invention:

1. A closure for storage vessels having a flange strengthened at the edge thereof, said flange being cut at a plurality of points around the same immediately above said strengthened edge, that portion of the strengthened edge below each of said cuts being bent inwardly to form locking lugs. 105

2. A closure for storage vessels having a flange having its edge curled or beaded, said beaded edge at spaced intervals being bent inwardly to form a plurality of jar engaging projections and said flange having immediately above each of said projections a slitted portion, thereby to facilitate the formation of said projections with less pressure and with less deformation of the flange. 115

3. A cap or closure for bottles and jars having a depending flange provided with a wire at the lower edge thereof, said wire being formed with a plurality of in-bent lugs and said flange being longitudinally slotted immediately above said in-bent lugs. 120

4. A cap or closure for bottles and jars comprising a flat top, a depending annular flange, the lower edge of said flange being curled or beaded, an endless wire housed within said curled portion of the flange, 125

- said wire having a plurality of in-bent lugs, and said flange being slitted longitudinally at points immediately above each of said in-bent lugs.
5. A metal cap for a glass container comprising a top having a depending flange, said flange having its lower edge curled or rolled, and also having immediately above said rolled edge the metal slitted at a plurality of points around the flange, the rolled edge being bent inwardly under such slots to form inwardly extending locking projections, and said flange also having reinforcing corrugations above said slots around the flange.
10. A metal cap for a glass container comprising a top having a depending flange, said flange having its lower edge curled or rolled, and also having the metal slitted immediately above said rolled edge at a plurality of points around the flange, the rolled edge being bent inwardly under such slots to form inwardly extending locking projections having substantially the same shape as the rolled edge intermediate the locking projections, said flange also having reinforcing corrugations above said slots around the flange.
15. A closure of the class described having a top and a depending flange provided with a rolled edge having inwardly extending locking projections formed from said rolled edge by first slitting the metal thereabove at intervals around the flange, then deflecting practically all of the rolled edge adjacent to each slitted portion to form said inwardly extending locking projections.
20. A closure of the class described having a top and a depending flange provided with a rolled edge having inwardly extending locking projections formed from said rolled edge by first slitting the metal thereabove at intervals around the flange, then deflecting practically all of the rolled edge adjacent to each slitted portion to form said inwardly extending locking projections, said flange having strengthening portions between the slots and the top of the cap.
25. A metal cap comprising a top and a depending skirt having a beaded or rolled edge adjacent to its lower edge, a plurality of slotted portions above the bead at intervals around the skirt, and inwardly extending locking projections formed from such bead below the slotted portions.
30. A metal cap comprising a top and a depending skirt having a bead or rolled edge adjacent to its lower edge, a plurality of slotted portions above the bead at intervals around the skirt, and inwardly extending locking projections formed from such bead below the slotted portions in such manner that practically all of the bead is deflected adjacent to said slotted portions inwardly from the outer margin of the skirt.
35. A rotatable metal closure for a container having divided threads or lugs and comprising a top and a depending skirt or flange having the lower edge provided with a beaded or rolled edge, and having at intervals around the skirt a plurality of slots, said bead having a plurality of portions thereof deflected inwardly to form container engaging projections, each located below one of said slots.
40. A rotatable metal closure for a container having divided threads or lugs and comprising a top and a depending skirt or flange having the lower edge provided with a substantially circular beaded or rolled edge and having at intervals around the skirt a plurality of slots, said bead having a plurality of portions thereof deflected inwardly to form container engaging projections, each located below one of said slots, and each of such projections having substantially the same cross section as the beaded or rolled edge between said projections.
45. A rotary metal cap for glass containers comprising a top and a strengthened or reinforced depending flange and a strengthened or reinforced lower edge, said flange having between said two strengthened portions slots located at intervals there-around, and the strengthened lower edge below each of said slots being inwardly pressed to form inwardly extending strengthened locking projections.
50. The method of making a rotatable metal cap which consists in providing a cup-shaped blank comprising a top and a depending flange, then subjecting the lower edge of the flange to pressure to form a rolled or beaded edge, then slitting the flange at intervals above such rolled edge and subjecting the rolled edge adjacent to said slotted portions to pressure radially of the cap to deflect portions of said beaded edge inwardly relatively to the major portion of the bead to form container engaging projections.
55. The method of making a rotatable metal cap which consists in providing a cup-shaped blank comprising a top and a depending flange, then subjecting the lower edge of the flange to pressure to form a rolled or beaded edge, then slitting the flange at intervals above such rolled edge and subjecting the rolled edge adjacent to said slotted portions to pressure radially of the cap to deflect portions of said beaded edge inwardly relatively to the major portion of the bead to form container engaging projections, while maintaining said inwardly pressed projections of substantially the same general formation as the rolled edge between the said projections.
60. The method of making a rotatable metal cap which consists in providing a cup-

shaped blank comprising a top and a depending flange, then subjecting the lower edge of the flange to pressure to form a rolled or beaded edge, then slitting the flange at intervals above such rolled edge and subjecting the rolled edge adjacent to said slotted portions to pressure radially of the cap to deflect portions of said beaded

edge inwardly relatively to the major portion of the bead to form container engaging 10 projections, and by pressure providing the flange above said slotted portions with reinforcing corrugations.
